UNITED STATES PATENT OFFICE.

JAMES A. BURDEN, OF TROY, NEW YORK.

MAGNETIC SEPARATOR.

SPECIFICATION forming part of Letters Patent No. 399,375, dated March 12, 1889.

Application filed January 18, 1889. Serial No. 296,725. (No model.)

To all whom it may concern:

Be it known that I, JAMES A. BURDEN, of the city of Troy, county of Rensselaer, State of New York, have invented a new and useful Electro-Magnetic Apparatus for the Separation of Magnetite from its Gangue, of which the following is a specification.

My invention relates to a mechanism for the separation of magnetite or magnetic oxide of iron from the gangue, with which it occurs in nature, and in cases where the presence of the gangue interferes with the making of good iron; and my invention is more particularly adapted for the treatment of that kind of iron ore called "apatite," wherein the magnetic oxide or magnetite is associated with lime phosphate.

My invention consists (as will be more fully detailed hereinafter in connection with its illustration) in the combination, with a roller made of iron that is divided in two parts in a plane that is at right angles to its axis, and having insulated bearings and being adapted to be rotated within a magnetic field, said roller being provided with means to remove from the magnetic roller the attracted magnetite, of another roller, made of wood or other non-conducting material, which is placed parallel to the magnetic roller, so as to leave a space between the two rollers for the passage of the previously-pulverized ore, with both of said rollers actuated to turn so as to move down the ore between them; a chute arranged under the magnetic roller to receive the magnetite; a chute arranged beneath the non-magnetic roller to receive the separated gangue, said last-named chute being made to utilize a draft-current of air that is drawn down between said rollers by an exhaust-fan that is arranged to operate within the chute that conveys away the gangue, said gangue-chute being made with pockets for the reception and removal of the gangue.

My invention also consists in the sub-combination of the parts where such parts perform specific function, as will be detailed in the claims.

Accompanying this specification, to form a part of it, are five plates of drawings containing twelve figures, illustrating my inven-

tion, with the same designation of parts by reference-letters used in all of them. Of these illustrations, Figure 1 is a top view of the apparatus. Fig. 2 is a side elevation of the mechanism. Fig. 3 is an end elevation of the apparatus. Fig. 4 is a section taken on the line $x' x'$ of Fig. 1. Fig. 5 is a cross-section showing a modification of the chute that receives the magnetite, also showing a varied position of the loop end of magnet. Fig. 6 is a perspective of the magnet, shown as detached, and illustrating the slot-stoppers used to close the outer ends of the transverse slots made in the pole ends of the magnet for the insertion of the magnetic-roller journals. Fig. 65 7 is a cross-section of the chute through which the gangue is conveyed away after having been separated from the magnetite. This figure shows also the position of the fan. Fig. 8 is a side elevation of the magnetic roller, shown as detached from the other mechanism. Fig. 9 is a side elevation of the non-magnetic roller. Fig. 10 is a longitudinal section of the magnetic roller. Fig. 11 is a longitudinal section of the non-magnetic roller. Fig. 12 is a cross-section of the magnetic roller taken on either of the lines $x^3 x^3$ of Fig. 8.

The several parts of the apparatus thus illustrated are designated by the letter-reference, and the function of the parts is described as follows:

The letter F designates the frame of the apparatus, and H a two-part hopper, through which the previously-powdered ore is supplied to the rollers.

The letter R' designates the magnetic roller, which is of iron and made in two parts, $m m$, between which latter there is arranged the non-conducting coupler C', which is preferably made of wood.

The letter J' designates the journals of the magnetic roller, one of which is arranged on each of the opposite ends of the latter. This roller has a hollow interior, I, and the parts $m m$ connect with the coupler by bolts d^3 .

The letter R² designates a roller that is made of wood, glass, or other non-magnetic material, and the letter J² designates the shaft or journals whereon said roller is operated to turn. This roller R² has a recess, E, made in

85

90

95

100

its roller-face for the entrance of the coupler of the magnetic roller when the two rollers are being rotated.

The letter M' designates a U-form magnet, 5 the pole ends of which are each made to have the transverse slot S for the entrance of the journals J' of the magnetic roller.

The letter b' designates insulated bearings, 10 in which the journals J' of the magnetic roller turn; and S², stoppers made to fit snugly into the slots S of the magnet outside of the entered journals of the magnetic roller, with the insulated bearings thereof outside of where the said journals pass through the magnet-slots. 15 These stoppers S² are made of the same kind of metal as the magnetic roller.

The letter b² designates bearing-boxes arranged to operate laterally in slideways n in the frame F by means of set-screws T, and 20 these bearing-boxes b² are for the journal ends or shaft J² of the non-magnetic roller, the function of the sliding bearing-boxes and set-screws being to adjust the position of the non-conducting roller R relatively to the magnetic 25 roller.

The letter C² designates a chute arranged with its upper open end beneath the magnetic roller, and the letter C³ another chute arranged with its upper open end beneath the 30 non-conducting roller. This chute C³, where extended downwardly and laterally, has arranged to be operated therein an exhaust-fan, F², the purpose of which is to create a strong atmospheric current down between the rollers to draw away from the magnetite fringing onto the magnetic roller the lighter gangue or lime phosphate. The letter P designates 35 pockets arranged in the chute C³ to receive the gangue or lime phosphate.

The letter D designates a scraper that is pivoted at p' and made to engage on its upper end with the surface of the magnetic roller to scrape therefrom the attracted magnetite, there being one of these scrapers arranged to engage with the surface of the 45 magnetic roller on each side of the coupler C'.

The letter W designates a circuit-wire that helically encircles the magnet with its ends connecting with a battery, B⁴.

The letter G designates a gear-wheel arranged on one of the outer ends of the non-conducting-roller journals J², adapted to receive power and to communicate it to said roller.

The letter P² designates a grooved pulley 55 arranged on the journal J², which is opposite to that at which the gear-wheel is located, which communicates power thereto.

The letter P³ designates a grooved pulley 60 that is preferably made of wood or glass or other non-magnetic material, and which is keyed to that journal, J', which is on the same side of the machine as the pulley P², and where said journal end projects beyond the 65 insulated bearing in which it turns; and the letter B² designates a cord belt that is crossed and arranged to communicate power and mo-

tion to the magnetic roller R' by means of the connection made by said belt with the pulleys P² and P³.

In the modification shown at Fig. 5 the base of the magnet is swung out laterally, where, resting on the insulated pedestal p³ and the chute C², it is shown as carried down nearly vertical, while in the other illustrations the said chute is made to slant downwardly and outwardly. The object of this modification is merely to give a nearly-vertical direction to the chute C², which may be desirable in some instances.

The operation of the mechanism thus described is as follows: With the wires of the magnet connected with a battery the magnet becomes excited and the roller R' becomes magnetic, and as the ore is supplied to the 85 hoppers H the magnetite is attracted to the face of the roller R', so as to adhere to the surface thereof at each side of the coupler C', while the gangue or lime phosphate, being non-magnetic and lighter than the magnetite, 90 is blown from its adhesion to the latter and conveyed away by the action of the fan through the chute C³. The magnetite adhering to the roller R' is scraped therefrom, so as to pass off in the chute C² by the doctors 95 or scrapers D. Should once passing the ore through the rollers not wholly remove the gangue, it may be passed through a second time. The ore when thus used should be pulverized sufficiently to separate the crystals of the magnetite from the gangue.

Having thus described my invention, what I claim, and desire to secure by Letters Patent, is—

1. In an apparatus for separating magnetite from a non-magnetic gangue, the combination, with an iron roller that is made in two parts and having an intermediate coupler of non-magnetic material, said iron roller at its outer ends being within the excited field of an electro-magnet and provided with journals and insulated journal-bearings, and having an insulated pulley at one end, of a non-magnetic roller arranged by the side of the metal roller, with an intervening space for the 110 passage of the ore, said non-magnetic roller being provided with journaled ends having bearings and constructed to receive motion, and with a pulley and belt to transmit the same to the insulated pulley of the metal 115 roller, substantially in the manner as and for the purposes set forth.

2. In an apparatus for separating magnetite from a non-magnetic gangue, the combination, with an iron roller that is made in two parts having an intermediate non-magnetic coupler, said iron roller at its outer ends being within the excited field of an electro-magnet and provided with journals having insulated bearings, with an insulated pulley at 125 one end, of a non-magnetic roller arranged by the side of the iron roller with an intermediate passage for the ore, said non-magnetic roller being provided with journaled ends and

bearings and constructed to receive motion, and with a pulley and belt to transmit power to the iron roller-pulley, a chute arranged beneath the metal roller, and a chute arranged beneath the non-magnetic roller, substantially in the manner as and for the purposes set forth.

3. In an apparatus for separating magnetite from a non-magnetic gangue, the combination, with an iron roller made in two parts connected by a non-magnetic coupler, said iron roller at its outer ends being within the excited field of an electro-magnet and provided with journals having insulated bearings with an insulated pulley at one end, of a non-magnetic roller arranged by the side of the iron roller with an intermediate space for the passage of the ore, and being provided with journaled ends having bearings, an actuating-gear at one end and a pulley and belt connecting with the pulley of the iron roller at the other end, a chute leading from the

iron roller, and a chute leading from the non-magnetic roller, which latter chute is provided with an interiorly-placed exhaust-fan, 25 substantially as and for the purposes set forth.

4. The combination, with the iron roller R', made in two parts, connected by a non-magnetic coupler, C', and having the end journal, J', of the electro-magnet M', having its 30 pole ends adjacent to the outer ends of the roller, and slotted at its pole ends for the side insertion of the roller-journals, insulated bearings for said journals outside of where passing through the electro-magnet, and stoppers S², made to close said slots where not occupied by the journals, as and for the purposes set forth.

Signed at 1130 Broadway, New York, this 2d day of January, 1889.

JAS. A. BURDEN.
